UNITED STATES PATENT OFFICE.

THOMAS G. BOWERS, OF NEW HAVEN, CONNECTICUT.

DESIGN FOR A SHOULDER-BRACE.

45,984.

Specification for Design.

Patented June 23, 1914.

Application filed March 31, 1914. Serial No. 828,629. Term of patent 7 years.

To all whom it may concern:

Be it known that I, THOMAS G. BOWERS, a citizen of the United States, residing in the city and county of New Haven and State of Connecticut, have invented a new, original, and ornamental Design for a Shoulder-Brace, of which the following is a specification, when taken in connection with the accompanying drawing.

In the accompanying drawing, the single

figure is a rear elevation of the shoulder brace, with the belt straps partly broken away.

I claim:

The ornamental design for a shoulder brace substantially as shown.

THOMAS G. BOWERS.
